(57) **CLAIM**

The ornamental design for a remote control for air conditioner, as shown and described.

DESCRIPTION

The patent or application file contains at least one drawing executed in color. Copies of this patent or patent application publication with color drawing(s) will be provided by the Office upon request and payment of the necessary fee.

1. Remote control for air conditioner

1.1 : Front

1.2 : Back

1.3 : Left

1.4 : Right

1.5 : Top

1.6 : Bottom

1.7 : Perspective

Description of the characteristic features of the design(s), or matter for which protection is not sought; Main design point: the overall shape; a view that best illustrates the point of the design: perspective view; possible use: remote control of air conditioner; The background color forms no part of the claimed design.
